UNITED STATES PATENT OFFICE.

JOHN CAHILL, OF NORFOLK, VIRGINIA.

SLIDING SWING DOOR.

Application filed July 17, 1924. Serial No. 726,495.

My invention relates to doors mainly intended for factories, warehouses, pier sheds, and the like with large door openings and little available head room, and particularly to doors of the multi-section type and whereof the sections are capable of vertical sliding and radial movement.

Objects of the invention are to provide a door consisting of a plurality of door sections, including a pivotally mounted upper section, the arrangement being such that the lower sections are capable of vertical sliding movement; to provide lifting elements for raising the sliding sections into coincidence with the upper section; to provide an upper section with guides to receive the sliding sections; to provide door operating mechanism such that when the sections are in coincidence a lifting moment will be established to cause them to swing radially to horizontal or other position; to provide for effectively balancing the forces to accomplish the ends stated; to provide a shaft suspension to accommodate the lifting elements and carrying differential supports for the counterbalance elements; to provide means operating automatically to prevent the sliding sections from moving relatively to the upper section after said sections have been swung radially; to provide for eliminating fire hazards; to provide lifting elements which function to raise the sliding sections, swing the sections as a unit radially, and to support them at will in any position; and to provide for supporting the door sections in such wise as to prevent individual or collective sagging thereof.

Other objects, as well as the nature, characteristic features, and scope of the invention will more readily be understood from the following description, taken in connection with the accompanying drawings, forming a part hereof, and wherein,

Figure 1 is a view in elevation of the improved door, the sections being shown in door-closing relation,

Figure 2 is a vertical section of the same,

Figure 3 is a view similar to Figure 2, the sections being shown in fully opened position, and

Figure 4 is a vertical sectional view, illustrating particularly the operation of the latch in the movement of the sections toward door-closing position.

In the embodiment chosen for purposes of illustration, there are three door sections, 1,

2, and 3. Obviously, the number of sections will vary according to circumstances. The upper section 3 is pivotally supported as at 4, through the agency of hinges connected to a suitable fixture immediately above the door opening. Secured to and overlying the side edges of section 3 are channel-like guides 5, whose office is to slidably receive the intermediate and lower door sections, 2 and 1. Fixed guides 7 are secured to the sides of the door opening. They terminate at the upper end slightly below the lower edge of the upper door section when in closed position, and are of a width for an appropriate distance from their upper ends to slidably receive both the intermediate and lower sections, as at 8; the remaining lower length of the guides slidably receiving the lower section only, as at 9.

The door sections, when in lowered or door-closing position slightly overhang or lap the next upper section, as at 10, Figure 2, thus insuring a proper initial movement of the sections in their opening movement; and the lower edge of the bottom section is provided with a lip or projection 11, to engage the other sliding section and lift the same in response to a raising movement.

An operating shaft 12 is mounted in brackets 13, secured above the door opening, and on this shaft, at appropriate intervals and in sufficient number, according to the size and weight of the door, are secured lifting drums 14, to each of which is attached a lifting element 15. The lower ends of the elements 15, which may be cables, chains or the like, are secured to pivotal elements or clevises 16, carried by the bottom door section, at or near its base and which may in fact be integrally or otherwise secured to the lip 11. The lifting drums are formed with spiral channels 17 to guide the cables in winding and unwinding, and such cables, as the shaft is turned, exert a direct lifting effort. Each cable or lifting element performs identical functions, namely to lift the lower sections into the guides on the sides of the upper section, to swing the sections as a unit radially of the pivotal support of the upper section, and to support the door in the open position.

To insure the results stated it is necessary to balance the forces established in the operation of the door, and the invention provides novel means for counterbalancing the door through drums fastened to the shaft 12,

whose axis it will be understood is horizontal and parallel to the top of the door. The drums are indicated at 18 and they are formed with differential spiral winding paths 19 for cable 20, supporting counterweights 21. The counterweight cable is wound on its drum reversely to the lifting cables in order to permit the pull of the counterweight to assist in winding up the lifting cables. The counterweight drum is here shown as designed for maintaining a substantially constant counterbalance, as it will be apparent that the increasing weight to be lifted as the sections are elevated, combined with the increased weight-leverage as the door sections are swung to a horizontal plane, must be compensated for if the action of the door sections is to be smooth and easy. This constant counterbalance effect is provided for by forming the counterweight drum of variable diameter, thus that portion with which the counterweight cable co-operates during the lifting of the lower section will be of a constant predetermined diameter, as at 22, that portion co-operating with the counterweight cable during the lifting of the lower and intermediate sections of the door, will have an increased predetermined diameter, as at 23, while that portion with which the counterweight cable co-operates in swinging the door sections into a horizontal plane is of maximum diameter, as at 24. Thus the counterweight proportionately increases the lifting force by winding from the increasing diameters of the counterweight drum, as such increased lifting force is required in the relative movements of the door sections.

It will of course be apparent that the invention contemplates varying the number and arrangement of the counterweight mechanisms as may be expedient or desirable; also that the constant effect of the counterweight may be gained with equal efficiency by varying the diameter of the lifting drums, conversely to that described for the counterweight drum, or by varying the diameters of both the counterweight and lifting drums, all such arrangements being contemplated as within permissible variations of the present invention.

An important feature of the invention is the provision of means to automatically prevent the sliding sections from escaping from the guides of the upper section after it has swung away from the stationary guides. As previously indicated, the sliding sections are raised into the guides on the upper section until they have passed above the stationary guides. At this position the downward moment around the hinge is less than the moment caused by the force required on the lifting cables to hold the sliding sections at their uppermost position. This lifting moment prevents the top section from swing-

ing back to its closed position. If the counterweights were lifted, that is to say, if a closing force was exerted on the operating chains, the lower sections would move out of the guides of the upper section and would be out of position to properly engage their stationary guides. I, therefore, provide the upper section with dogs or latches 25. The latches 25 are pivotally supported in brackets 26, and have hook-like terminals 27, which operate by gravity to engage the bottom of the lowermost section 1. The latches are provided with stops or lateral pins 28, which in the normal closing movement of the door are adapted to ride into contact with lugs 29, on the upper ends of the fixed guides 7, and thus displace the hook ends of the latches from beneath the lower edges of the lower door section 1. Thus the latches operate automatically, both in moving to perfect a holding of the door sections against downward movement, and in releasing such sections for downward movement, the latter operation taking place, however, only when the lower sections are accurately in position to enter the fixed guides 7, for proper closing movement.

The shaft 12 may be provided with any usual operating means, here shown as a chain 30, passing endlessly over a sprocket 31 arranged at one side of the door, and operating through appropriate gearing 32 to turn the shaft 12 in the desired direction. The lower edge of the lower section 1 may be provided with rollers 33, to relieve friction incident to the outward pull of the lifting cables in the upward and downward movement of this door section. Angle strips 34 are preferably secured to the side margins of the door opening, to serve as weather strips, and as a guide to receive the upper door section when in closed position.

Another important feature of the invention is the provision of means to prevent rattling of the door sections, and particularly of the intermediate sliding section, and to keep the sections in relatively close overlapping relation in order to eliminate fire hazards. Such means is here shown by way of example, as marginal lugs or overhangs 35 secured near the top edge of the intermediate door section, and operating by contact with the guides to hold the adjoining door sections in proper overlapping relation. In order to minimize the friction of the parts, the bearing portion of the lug 35 is formed as a nose 36.

In operation, assuming the door closed, force is exerted on the chain 30 to move the shaft 12 in a direction to cause the counterweight drum to unwind its cable, and the lifting drums to wind up the lifting cables. The upward movement continues until the lower section overlies the intermediate section, and both overlie the upper section. At

this point the lifting power of the cables cause a pivot movement on the hinges 4, and this lifting moment is equal to the product of the force on the lifting cables and the distance 5 between the center of the hinge bearings and the center of the rope at that point on the lifting drums which is farthest from the wall. Obviously, this lifting moment may be increased or decreased by varying the distance of the shaft 12 from the wall. As the 10 lower and intermediate sections are no longer held by the guides 7, all sections swing outwardly into substantially a horizontal plane. The latches 25 have meanwhile automatically operated to hold the lower and 15 intermediate door sections in proper relation to the upper section. During the swinging movement of the door sections, the downward moment varies in magnitude through 20 out such travel, and this variation is compensated for in the constantly-increasing counterbalance force provided in the variable diameter counterweight or lifting drums, either or both, the maximum counterbalance force being of course provided for 25 as the door reaches its extreme open position.

In the closing door movement, the sections maintain their relative positions, 30 through operation of the latches 25, until the lower door section 1 is in position to enter the upper ends of the fixed guides, which guides may, if desired be slightly flared at their upper ends. At this point the latches 35 are automatically moved to release positions, and the door sections return to closed positions in a smooth and even operation.

The advantages of this type of door are that its design will permit of safely supporting and operating closures of great size 40 and weight.

A further important feature of the invention is the elimination of conditions tending to sagging of the door sections. This is accomplished through the medium of the hinge supports for the upper section, and through the medium of the cables acting in conjunction with the rigid heel or lip 11.

Manifestly, the door sections may be of 50 any usual or preferred type. That is to say, they may be solid metal constructions or of sectional or slat type, with glass or other transparent sections; or they may be constructed of wood; or they may embody a 55 composite structure of wood and metal.

Having thus described the invention, what is claimed as new, is:—

1. A door having an upper section mounted for swinging movement, a lower section 60 mounted for relative sliding movement, guides for compelling a sliding movement of the lower section into coincidence with the upper section before permitting swinging movement of such upper section, and lifting cables connected to the lower section 65

and acting directly through such connection alone to first slide the lower section and then swing both sections.

2. A door having an upper swinging section, a lower sliding section, fixed guides to 70 receive the lower section, guides carried by the upper section to receive the lower section as the latter is raised, and means carried by the upper section guides to engage and hold the lower section against sliding 75 movement relative to the upper section when such lower section leaves the fixed guides.

3. A door having a hinged upper section, a relatively slideable lower section, lifting cables connected to the lower section and acting through such connection alone to first 80 slide the lower section and then swing both sections about a common center, and means for counterweighting the movements of the sections.

4. A door having a hinged upper section, a relatively slideable lower section, lifting cables connected to the lower section and acting through such connection alone to first 85 slide the lower section and then swing both sections, and guides to prevent swinging of the sections until the lower section has been moved into coincidence with the upper section.

5. A door having a hinged upper section, 90 a relatively slideable lower section, lifting cables connected to the lower section and acting through such connection alone to first slide the lower section and then swing both 95 sections about a common center, and means for counterweighting the movements of the sections, said means being arranged to accurately compensate for the increasing force required in the movements of the sections and for sustaining them in operative position.

6. In a door of the sliding and radially swinging type, the combination with a pivoted door section and sliding door sections, 100 of fixed guides for the sliding door sections, guides carried by the pivoted door section to receive the sliding sections, and dogging mechanism to hold the sliding sections in the last named guides when the door sections 105 are swung radially.

7. In a door of the sliding and radially swinging type, the combination with a pivoted door section and sliding door sections, 110 of fixed guides for the sliding door sections, guides carried by the pivoted door section to receive the sliding sections, dogging mechanism to hold the sliding sections in coincidence with the pivoted section, and means in the path of the dogging mechanism to trip the same and permit the sliding sections 115 to enter the stationary guides in a normal closing movement of the door.

8. In a door of the multi-section sliding and swinging type, the combination with 120 sliding door sections and their guides, of 125

means for eliminating flame passage, including a distance element mounted relatively to the sections and guides and operating to maintain flush contact of the sections.

5. 9. In a door of the multi-section sliding and swinging type, the combination of overlapping door sections and means to prevent sagging thereof comprising hinge mountings for the upper edge of the top section, a rigid heel extending along the bottom edge of the lower section and having an element engageable with the other sections, whereby the sections individually and collectively are maintained in straight line relation with the hinge support, and means for supporting 20 and lifting the sections and arranged to exert a direct pull on the heel portion of the lower section.
10. 10. In a door of the multi-section sliding and swinging type, the combination of overlapping door sections and means to prevent sagging thereof comprising hinge mountings for holding the top section against other than a swing movement, a rigid heel to reinforce the bottom section and adapted to engage the other sections, and means for supporting and lifting the sections and secured to the bottom section in the region of 25 the heel.

15. 10. In a door of the multi-section sliding

and swinging type, the combination of overlapping door sections and means to prevent sagging thereof comprising hinge mountings for the upper edge of the top section, a rigid heel extending along the bottom edge of the lower section and having an element engageable with the other sections, whereby the sections individually and collectively are maintained in straight line relation with the hinge support, and means for supporting 20 and lifting the sections and arranged to exert a direct pull on the heel portion of the lower section.

In testimony whereof I affix my signature.

JOHN CAHILL.
